SAFETY LOCK FOR ELECTRIC SWITCHES

Benjamin E. Getchell, Plainville, Conn., assignor
to The Trumbull Electric Manufacturing Com-
pany, Plainville, Conn., a corporation of Con-
necticut

Application February 6, 1933, Serial No. 655,335

3 Claims. (Cl. 200—87)

My invention relates to electrical switches and particularly to the type of disconnecting switches which are used for controlling circuits of high capacity and in which circuits the current is derived from a source in which the power may vary so greatly as, at times to cause the electrical current to greatly exceed the rated or safe current-breaking capacity of the switch.

In certain types of switches, usually made in large sizes for controlling power circuits, it is at times extremely dangerous to open the switch when the current is on. Under these conditions the rule is that the switch shall not be opened while the current is flowing, that is, the circuit must be opened at some other point by means of a circuit breaker of greater capacity before it is safe to open that particular switch.

Notwithstanding the existence of such rules, careless and ignorant individuals may attempt to open such switches. It is the object of my invention, therefore, to provide means for preventing the opening of the circuit through such a switch while current is flowing in the line.

Switches of this type are usually enclosed in a box having an external operating handle and a cover hinged to the box and, in case of a heavy over-load in the circuit, such switches are extremely dangerous to operate to open the circuit because the operator naturally stands in front of the cover directly in the danger zone. If the switch is opened under such over-load conditions when the box cover is open, the operator is usually standing in front of the contacts and thus directly in the path of any arc or flash that may occur and if the switch is opened under such over-load conditions when the cover is closed, the arc is sometimes so intense as to cause an explosion of sufficient magnitude to blow the cover open or entirely away from its catches, latches and hinges and directly into the operator's face.

In many instances, operators have been injured and severely burned while opening a switch under such over-load conditions and, in fact, a recent instance in which the operator was actually killed, directed attention to the necessity for providing means which would positively prevent the opening movement of the switch under such over-load conditions and thus protect the operator as well as to prevent damage to the switch or other correlated parts.

Boxes for enclosing switches of this type are usually provided with some sort of an independent spring catch or latch for holding the cover closed under normal conditions and are some-

times provided with an interlocking means for co-operation with the switch to lock the cover closed when the switch is on but which will move or be moved so as to permit the cover to be opened when the switch is in the off position.

These interlocking means add greatly to the cover latching power of the independent spring catch when the switch is fully closed in the on position but they are often arranged so to move away from the fully latched position as the switch is being opened so that, when the switch contacts have reached the arcing position, the cover latching power of the interlocking means has been so greatly reduced that it is left for the independent spring latch to bear the brunt of any explosion that may occur within the box.

It has been found in practice however that the combined cover latching power of the independent catch or latch and any usual interlocking means is not great enough to hold the cover closed when the switch is opened under excessive over-load conditions, therefore the special object of my invention is to provide a means for also locking the switch mechanism so that the switch cannot be opened while excessive over-load conditions exist but which will release the operating mechanism so that the switch may be opened as soon as the current has returned to normal conditions or to a predetermined percentage of over-load.

Another object is to provide a switch locking means of the character described which is normally inactive but which will automatically operate to lock the switch against opening movement when the current is abnormal or excessive and which will automatically release the switch as soon as the current returns to normal conditions or to a predetermined percentage of overload.

Another object is to provide a magnetically operated switch-locking means which is automatically operated by the circuit to be controlled but which is not directly connected or in series with the circuit.

Another object is to provide a means for locking an electrical switch against opening movement under overload conditions and which means includes a magnet core and an armature for the core, the core and the magnet being so positioned, with respect to the path of the current to be controlled, that the magnetic flux of the current will energize the magnet core and no windings of any description will be required for the core and no electrical connections to any correlated parts or to the circuit are required for energizing the core.

Another object is to provide a safety locking

device which may be readily applied to standard types of switches without material alteration in the general switch construction.

Another object is to provide a safety lock which can be applied to previously installed switches.

Another object is to provide a safety lock of this character which is positive in operation but which is simple and inexpensive.

For the above purposes I have provided an electromagnetically actuated lock for preventing the opening movement of the switch while the volume of current is greater than can be safely controlled by the switch.

An electro-magnet with a core and a movable armature is accordingly provided which is mounted so as to surround some of the current carrying parts, preferably one of the hinge posts of the usual knife blade type switch, so that when current is flowing through the post of the switch the resultant magneto-motive force sets up magnetic lines of force in the electro-magnet which is thus energized to hold the armature closed. Between this armature and a movable member of the switch or its actuating mechanism is located an interlocking device. The switch construction preferably embodies a plurality of these electro-magnetic devices connected to a common interlocking member. So long as an excessive current is flowing through the switch the magnets are energized and the actuating mechanism held in its locked position. When the current decreases to a safe amount or when the circuit is otherwise opened the magnets are de-energized and the locking means is withdrawn by a suitable spring means and the interlocking mechanism is released.

Fig. 1 is a perspective view of one form of construction embodying my improvements and showing the parts in the interlocked position.

Fig. 2 is a fragmentary view showing the parts of the interlocking mechanism on a larger scale in a position to allow the switch to be opened.

Fig. 3 is a detail sectional view showing the arrangement of one of the electro-magnetic devices.

Fig. 4 is an edge view of one of the electro-magnetic devices.

Figs. 5 and 6 are detail views of one form of interlock.

The drawing shows the invention as applied to a switch for a three-wire system, having the line terminals 6, 7 and 8 and the load terminals 9, 10 and 11 with movable switch blades 12, 13 and 14 of the conventional hinged type. Each blade is hinged to a post 15 at its lower end and coacts with a stationary jaw member 16 at its upper end when the circuit is closed.

Jaws 17 and 18 may be provided for a suitable fuse or other protective device in each branch of the circuit. In the usual form of construction the hinge post 15 and accompanying fuse jaw 17 are mounted on a common conducting plate 19.

The electric conducting members above described are all mounted in the usual way upon an insulating base 20 which is usually enclosed in a box 21.

The switch may be actuated in any suitable manner. In the form shown the various hinged blades are connected by an insulating crossbar 22 and an oscillating crank shaft 23 is pivotally supported at the opposite sides of the box and connected to the crossbar 22 by one or more links 24. The switch is provided with an external actuating handle 25, whose hub 26 is suitably con-

nected with the crank shaft 23 in any suitable manner.

A pivoted latch 27 is arranged adjacent the shoulder 28 of the hub and is normally held out of engagement by the tension of spring 29.

The latch actuating bar 30 is mounted transversely of the box and adapted to engage the shoulder 31 on the latch 27. This bar 30 is preferably made of non-magnetic material.

The electro-magnet, consisting of the preferably laminated core member 32 and the armature 33 hinged at 34, is mounted to surround the hinge post 15 and the swinging end of the armature 33 is connected at 35 to the bar 30. The magnet is mounted upon an insulating block 36, to which it may be secured by screws 37, or by any suitable rivet means and the block 36 may be secured, for instance, to the plate 19 by screws 38. It will thus be seen that the bar 30 is supported by the armatures 33, 33 to reciprocate between the plate 19 and the lower part of the magnet core 32.

The adjusting spring 39 is supported in a bushing 40 in the post 15 so that the spring tends to move the armature away from the magnet core 32 or to the left as viewed in the drawing.

Retractile spring 39 may conveniently be provided with a means to allow for its adjustment in order to operate under predetermined circuit conditions. In the form shown in Fig. 3 the spring bears at one end against the armature and its other end is enclosed in a thimble form of bushing 40 which is threaded, in screw fashion, into the jaw members 15 of the hinge jaws. The closed end of the bushing 40 may be provided with the usual slot or any other suitable means for turning the bushing to adjust the tension of spring 39.

When the switch is closed and an overload occurs, the armatures are drawn up to the respective cores and each armature with its core makes a closed magnetic circuit around the conductor post 15. The magneto-motive force thus gives rise to lines of force through the magnetic circuit and tends to move the armature and to hold the parts in the closed circuit position with the bar 30 pressing the latch 27 into the path of the projection 28 of the hub 26 to prevent operation of the handle or other actuating member.

When the overload condition ceases or when the current flowing is normal or less than sufficient to overcome the bias of the springs 39, the springs tend to move the armatures so as to retract the locking bar 30 and the spring 29 retracts the latch 27.

It will thus be seen that means is provided for preventing the actuation of the switch except when the circuit conditions are such that it is safe to do so.

Since the operation of my invention depends merely upon the production of magnetic lines of force around a current carrying conductor, it is independent of the character of the current, which may be either direct or alternating, provided that the construction of electro-magnet 32 and armature 33 are suited for the character of flux induced therein, as is well known in the art, and that retractile springs may be suitably adjusted for the tractive force exerted by the electro-magnet 32, which will differ with differing types or capacities of currents.

As certain electrical systems may have non-uniform values of current in the different conductors thereof, it is preferable that at least one electro-magnet of my device be arranged to be

excited by the conductor which carries the greatest value of current, to the end that the switch remain locked when the current in any conductor exceeds the predetermined safe minimum value.

- 5 From the foregoing it will be clear that I have provided a safety locking device which is inactive under normal circuit conditions inasmuch as its presence does not in any way affect the usual operation of the switch to which it may be applied, however, when an overload occurs in the circuit, or in any pole of the circuit, the locking device will instantly and positively operate to lock the switch against its opening movement and will retain its switch locking position until the overload period has passed. It will also be clear that I have provided a form of electro-magnet which, together with its method of mounting makes it possible to automatically operate a switch lock in a positive and practical manner and without the usual windings for the core of the magnet and without any direct electrical connection with the circuit to be controlled.

25 While I have shown and described my switch lock as movable to engage a portion of the hub of the operating handle of an enclosed switch of the interlocking type, it is quite clear that the locking bar of my construction may be arranged to lockably engage any portion of any type of switch operating handle without departing from the scope of my invention.

I claim:

1. A switch construction including an enclosure having a cover, stationary and movable contacts within said enclosure, external means for operating said movable contacts, a magnet having an armature within said enclosure, a latch operably connected with said armature within said enclosure, said magnet being adapted to move said latch into position to prevent the

movement of said external operating means when the current in the circuit is excessive and a spring for normally retaining said latch in inoperable position when the circuit is normal and to automatically move said latch into inoperable position when excessive current conditions have ceased, all of the parts of the magnet, the armature and the latch being inaccessible when the cover is closed.

2. In an enclosed electric switch, a box, a cover for said box, stationary and movable contacts within said box, an external operating handle having a hub supported in a wall of the box and means of connection with the movable contacts to actuate the same, an inaccessible spring retracted latch within said box adapted to engage the hub to prevent the manual operation of the switch under excessive overload conditions, a magnet having an armature within said box adapted to be actuated by current passing through said switch and an inaccessible rod connected to said armature and adapted to engage said latch to operate the same in opposition to said spring.

3. An enclosed switch including a box having a cover, stationary and movable contacts mounted within the box, an external pivoted actuating handle carried by the box, means of connection between said handle and the movable contacts of the switch whereby the switch may be manually actuated to open and close the circuit, an electro-magnet having an armature adapted to be actuated solely by excessive current flowing through the switch, an inaccessible latch within said box adapted to be actuated by the armature to prevent the manual operation of the switch under excessive overload conditions and spring means for retracting said latch.
